DUMPING RECEPTACLE.

1,424,634.

Specification of Letters Patent. Patented Aug. 1, 1922.

Application filed August 29, 1921. Serial No. 496,461.

To all whom it may concern:

Be it known that we, FRITZ FINCKH, residing at Essen, Germany, and PAUL KRÜGER, residing at Essen, Germany, both subjects of the Republic of Germany, have invented a certain new and useful Improvement in Dumping Receptacles, of which the following is a specification.

This invention relates to dumping receptacles with the bottom tiltable towards both sides and connected to the side walls by a force-closed hinged connection which automatically is released in the tilting movement of the bottom towards the dumping side, 15 while it is maintained on the opposite side and transmits the movement of the bottom to the side wall on the side which is movable relatively to the bottom.

The object of this invention is a dumping receptacle of the kind mentioned, in which a separate mechanism is provided for each side wall, by which mechanism the latter, when the discharge takes place on its side, in the tilting movement of the bottom towards 25 said side, is so controlled that an enlargement of the discharge opening is effected and that, in tilting towards the opposite side in which case the force-closed hinged connection between the side wall and the bottom is maintained, no action is exerted on this side 30 wall by said mechanism.

In the drawing, in which an embodiment of the invention as applied to a railway dumping car is shown,

35 Fig. 1 is a cross section through the car in the loading position,

Fig. 2 a similar section of the car in dumping position towards one side, and

40 Fig. 3 a similar section of the car in dumping position on the other side.

On the underframe A of the car are rigidly secured parallel to each other the two end walls A¹. Also to the underframe A, at the front and rear end of the car, 45 are placed two bearings a² symmetrical to the central longitudinal plane of the car. Said bearings are to receive two through shafts B, on which are mounted, in opposite pairs, crank arms b¹. The crank arms b¹ 50 are each connected to the bottom C of the car by a rod D. Further to the underframe are secured abutments a³, permitting an inwardly directed rotation only, of the crank arms b¹, when the latter engage them.

55 Again on the bottom C of the car, abutments

c¹ for the rods D are provided, which permit likewise said links to turn only inwardly.

Each of the two side walls E of the car is provided at its lower edge with a laterally open bearing e¹, which engages, in the loading position of the car (Fig. 1), with pins c² of the bottom C so, that there is formed in a well known way a force-closed hinged connection, which automatically is released 60 on the discharge side, in the tilting movement of the bottom, while this connection is maintained on the opposite side. At their upper edge the side walls rest, in the loading position of the car, in open bearings a⁴ provided on the end walls A¹. The side walls E are guided by links F, which are pivoted 65 on the end walls A¹.

On the front as well as on the rear end of the bottom C, and on each side of the central longitudinal plane of the car, is mounted an angle crank composed of two arms G and G¹ rigidly connected together. The arm G of each angle crank is connected with the side wall E, lying on the opposite 70 side of the central longitudinal plane, by a connecting rod H, which passes through a slot (not shown) in the bottom C, the pivot connecting said rod H to the side wall being co-axial with the respective bearing 75 e¹. The second arm G¹, of the angle crank G G¹, is connected with a crank arm k¹ by a rod J, said arm being secured on a shaft K, journalled in the underframe A on the same side of the central longitudinal plane. 80 These parts are so arranged that the axis of the pivot connecting the crank arm G¹ with the rod J, coincide, in the loading position of the car (Fig. 1), with the common axis 85 of the pivots which connect the crank arms b¹ journalled on the opposite side of the central longitudinal plane, with the corresponding rods D.

Furthermore, in the loading position of the car (Fig. 1), the crank arms k¹ are 100 turned in the opposite direction to the arrow x beyond their inner dead center position, and the crank arms G are turned in the direction of the arrow y beyond its outer dead center position, through a certain small 105 angle. Both the shafts K, rotatable by hand wheels k² and locked against rotation in the direction of the arrow x when the car is in the loading position, also carry at each end a crank arm k³, which is connected by a rod 110

M with a crank arm b^2 , mounted on the shaft B and extending in the opposite direction to the crank arm b^1 .

When the car is loaded (Fig. 1), the load exerts a pressure on the side walls E in the discharge direction. Since the bearings e^1 of the force-closed links connecting the side walls with the bottom are open laterally, the pivot pins c^2 cannot take up these pressures.

They are, however, taken up by the rods H and further by the crank arms G. Since the latter are near their dead center position, they afford an automatic lock so that the car is secured in a high degree against an unintentional discharge. In the event that this automatic locking action should become released by blows in the travel of the car, and, at the same time, the locking of the shafts K against rotation in the direction of the arrow α should be ineffective, a further guarantee against unauthorized discharge is provided for in that the crank arms k^1 are in the vicinity of their inner dead centers. Accordingly, when the crank arms G turn in the direction of the arrow y under the influence of the forces transmitted by the connecting rods H in the direction of the arrow y , the crank arms k^1 can only turn through a small angle in the direction of the arrow α , till they reach their dead center position.

This is obviously practically immaterial.

When the car is to be dumped on the right hand side, for example (Fig. 2), the crank arms k^3 , located to the left of the central longitudinal plane, after the lock of the shaft K is released, are turned inwardly a small amount in the direction of the arrow α by means of the hand-wheels k^2 . This rotation is transmitted by the links M and the crank arms b^2 to the crank arms b^1 , so that the latter are also turned inwardly. Under the weight of the load the bottom C then tilts automatically towards the right, turning on the pivots which connect the left hand, at this time remaining stationary, crank arms b^1 with the corresponding rods D, resting against the abutments c^1 and therefore moving together with the bottom.

Simultaneously with the left hand crank arms k^3 , the crank arms k^1 , rigidly connected to them, are turned. This movement is transmitted by the rods J to the angle cranks G G^1 and, from there, to the right hand side wall E, which turns outwardly in the bearings a^4 . This movement of the side wall can take place unhindered, since the bearing e^1 of the force-closed pivotal connection $e^1 c^2$, connecting the bottom and side wall, is laterally open and therefore said force-closed connection is released automatically. The side wall E then swings in the direction to enlarge the discharge opening.

During the tilting movement of the bottom, the force-closed connection between it and the left side wall E is maintained, so

that the side wall is raised in the usual way and moved inwardly. The rod H, which engages this side wall, maintains at this time its position unchanged relatively to the bottom, since the axis of the pivot, which connects the right hand rod J with the corresponding crank arm G^1 , coincides with the pivotal axis of the bottom and, therefore, the crank arm G^1 cannot make a movement relative to the bottom. The pivotal connection between the left side wall and the bottom, therefore, remains secured even during the dumping, by the left hand rod H.

In the return of the bottom into the loading position, the crank arms $k^1 k^3$ (lying to the left of the central longitudinal plane) are turned back, in the direction opposite to the arrow α , into their original position. This movement of the crank arms results in the bottom of the car being also turned back into its original position, the side walls E also returning to their original position simultaneously.

The dumping of the car towards the left side (Fig. 3) requires no special description, since the various operations correspond exactly to those occurring when the car is dumped towards the right. It may merely be stated that, in contradistinction to the first case, the left hand crank arms $k^1 k^3$ remain stationary and the movement of the bottom and of the right hand side wall is accomplished by the crank arms $k^1 k^3$, lying to the right of the central longitudinal plane of the car.

I claim:

1. A dumping receptacle of the class described having an underframe, a bottom tiltable to either side, two side walls, force-closed hinged connections between the side walls and the bottom, said connections on the one hand releasing the side wall at the discharge side when the bottom is tilted, and, on the other hand, transferring the movement of the bottom on to the side wall at the opposite side, and means permanently connected to each side wall and actuated by the tilting of the bottom for rocking outwards the side wall at the discharge side when the bottom is tilted.

2. A dumping receptacle of the class described having an underframe, a bottom tiltable to either side, two side walls, force-closed hinged connections between the side walls and the bottom, said connections, on the one hand releasing the side wall at the discharge side when the bottom is tilted, and, on the other hand, transferring the movement of the bottom on to the side wall at the opposite side, and means for rocking outwards the side wall at the discharge side when the bottom is tilted, comprising a connecting rod, an angle crank, a double crank arm pivoted to the underframe and connected to said angle crank by a rod, a

second double crank arm connected to said first-named double crank arm by a rod and a rod connecting said second double crank arm to the bottom.

- 5 3. A dumping receptacle of the class described having an underframe, a bottom tiltable to either side, two side walls, force-closed hinged connections between the side walls and the bottom comprising laterally open bearings on one of these parts and pins carried on the other part and engaging said bearings so as to permit to release the side wall at the discharge side when the bottom is tilted, and to maintain said engagement with the other side wall in order to transfer the movement of the bottom on to this last-named side wall, and means connected to said side walls and actuated by the tilting of the bottom for rocking outwards 20 the side wall at the discharge side when the bottom is tilted.

4. A dumping receptacle of the class described having an underframe, a bottom tiltable to either side, two side walls, force-closed hinged connections between the side walls and the bottom, said connections, on the one hand, releasing the side wall at the discharge side when the bottom is tilted, and, on the other hand, transferring the movement of the bottom on to the side wall at the opposite side, a transmission between said bottom and said side walls, including a pair of crank arms journaled on said bottom, rods connecting one end of each of said crank arms to one of said side walls, the pivotal axis of said connecting rods at the respective side wall coinciding with the axes of said force-closed hinged connections, and means for so guiding said connecting rods, 40 as to enable them, at the side opposite to the discharge side, to maintain their position relatively to the bottom when the latter is tilted.

5. A dumping receptacle of the class described having an underframe, a bottom tiltable to either side, two side walls, force-closed hinged connections between the side walls and the bottom comprising laterally open bearings on one of these parts and pins carried on the other part and engaging said bearings so as to permit to release the side wall at the discharge side when the bottom is tilted, and to maintain said engagement with the other side wall in order to transfer the movement of the bottom on to this last-named side wall, a transmission between said bottom and said side walls including a pair of crank arms journaled on said bottom, rods connecting one end of each of said 55 crank arms to one of said side walls, the pivotal axis of said connecting rods at the side wall coinciding with the axes of said force-closed hinged connections, and means for so guiding said connecting rods as to enable them, at the side opposite to the

discharge side, to maintain their position relatively to the bottom when the latter is tilted.

6. A dumping receptacle of the class described having an underframe, a bottom tiltable to either side, two side walls, force-closed hinged connections between the side walls and the bottom, said connections, on the one hand, releasing the side wall at the discharge side when the bottom is tilted, and, 70 on the other hand, transferring the movement of the bottom on to the side wall at the opposite side, and means connecting each side wall to said bottom and including a crank arm journaled on said bottom and a rod connecting said arm to said side wall, said crank arm and connecting rod being so arranged that said crank arm assumes a position near a dead center when said bottom is in the loading position. 85

7. A dumping receptacle of the class described having an underframe, a bottom tiltable to either side about an axis lying each on the opposite side of the central longitudinal plane of the receptacle, two side walls, 90 force-closed hinged connections between the side walls and the bottom, said connections, on the one hand, releasing the side wall at the discharge side when the bottom is tilted, and, on the other hand, transferring the 95 movement of the bottom on to the side wall at the opposite side, a pair of transmissions between said bottom and said side walls and adapted, when the bottom is tilted, both to rock outwards the side wall at the discharge 100 side and to maintain said connection between the bottom and the other side wall, said transmissions including each a movable member so connected to said bottom as to partake, at the discharge side, in the tilting 105 movement of the bottom and to remain at rest at the opposite side.

8. A dumping receptacle of the class described having an underframe, a bottom tiltable to either side about an axis lying each 110 on the opposite side of the central longitudinal plane of the receptacle, two side walls, force-closed hinged connections between the side walls and the bottom, said connections, on the one hand, releasing the side wall at 115 the discharge side when the bottom is tilted, and, on the other hand, transferring the movement of the bottom on to the side wall at the opposite side, a pair of transmissions between said bottom and said side walls and each comprising a crank arm journaled on said bottom, a rod connecting said crank arm to one of said side walls, a second crank arm journaled on said bottom and rigidly secured to said first crank arm, a second rod 120 connecting said second crank arm to a third crank arm journaled on the underframe, a movable member partaking, at the discharge side, in the tilting movement of said bottom 125 and remaining at rest on the opposite side, 130

and positively connected to said third crank arm.

9. A dumping receptacle of the class described having an underframe, a bottom tiltable to either side about one of two fixed axes lying each on opposite sides of the central longitudinal plane of the receptacle, two side walls, force-closed hinged connections between the side walls and the bottom, said connections, on the one hand, releasing the side wall at the discharge side when the bottom is tilted, and, on the other hand, transferring the movement of the bottom on to the side wall at the opposite side, a pair of transmissions between said bottom and said side wall and each comprising a crank arm journalled on said bottom, a rod connecting said crank arm to one of said side walls, the pivotal axis of said rod at the side wall coinciding with the axis of the respective force-closed hinged connections, a second crank arm journalled on said bottom and rigidly secured to said first crank arm, a second rod connecting said second crank arm to a third crank arm journalled on the underframe, the pivotal axis of the connection of said second rod with said second crank arm coinciding, in the loading position of the receptacle, with the tilting axis lying opposite the discharge side, of the bottom, a movable member partaking, on the discharge side, in the tilting movement of said bottom and remaining at rest on the opposite side, and positively connected to said third crank arm.

10. A dumping receptacle of the class described having an underframe, a bottom tiltable to either side about an axis lying each on the opposite side of the central longitudinal plane of the receptacle, two side walls, 40 force-closed hinged connections between the side walls and the bottom, said connections, on the one hand, releasing the side wall at the discharge side when the bottom is tilted, and, on the other hand, transferring the 45 movement of the bottom on to the side wall at the opposite side, a pair of transmissions between said bottom and said side walls and each comprising a crank arm journalled on said bottom, a rod connecting said crank arm to one of said side walls, a second crank arm journalled on said bottom and rigidly secured to said first crank arm, a second rod connecting said second crank arm to a third crank arm journalled on the 50 underframe and assuming a position near a dead center when the receptacle is in the loading position, a movable member partaking, on the discharge side, in the tilting movement of said bottom and remaining at rest on the opposite side, and positively connected to said third crank arm.

The foregoing specification signed at Essen, Germany, this 2nd day of August, 1921.

FRITZ FINCKH.
PAUL KRÜGER.

In presence of—

JOHANN DECKERS,
CARL MÜLLER.
